PACKAGING APPARATUS AND PROCESS
Claude K. Lee, Bourbonnais, Ill., Harry E. Rothmann, Valhalla, N.Y., William C. Storey, Kankakee, Ill., and George M. Woodruff, Thornwood, N.Y., assignors to General Foods Corporation, White Plains, N.Y., a corporation of Delaware

Filed Nov. 22, 1963, Ser. No. 325,686
36 Claims. (Cl. 53—24)

This invention relates generally to an apparatus and method for forming and wrapping in individual packages a malleable, semi-solid product, capable of being molded into a desired packaged configuration. More particularly, the invention relates to an apparatus and method of the above character wherein a wrapper blank having easy-opening features is fabricated from roll stock, applied to a volumetrically measured quantity of the product formed by the apparatus into a desired shape and then sealed to provide an air and moisture barrier for the product, all of these operations being performed in a continuous, high speed, fully automatic manner.

The invention is disclosed herein in an embodiment adapted for packaging within a contour wrapper a food product processed into a ground or shredded condition, the individual shreds or pellets of which are combined and molded into a disclike or waferlike form which will hereinafter be referred to as a patty, although it should be understood that the precise nature of the product or the precise form into which it is molded are not essential aspects of the inventive concepts herein disclosed. Also, in the present embodiment of the invention use is made of a wrapper material which is transparent and moisture-impervious to a relatively high degree, since the ability to see the product within the wrapper and the retention of moisture within the product are valuable attributes in the merchandising of products of this character. However, as will be apparent from the following description, the invention is in no way dependent upon wrapping material having these attributes.

In carrying out the invention, use is made of an endless chain of unique and novel construction strung about and reaching between two separated and opposed turret members, each having rotating sprocket means cooperating with the chain. The chain is driven continuously, and each link thereof comprises a mold into which a measured quantity of the loose product is placed to be formed by cooperating members into the desired configuration such as that of a patty. The input of the loose bulk product, measuring thereof and forming thereof into the patty shape is accomplished while the individual links of the chain pass around one of said turret members, and sealing of the edges of the wrapper blank to complete the packaging operation is accomplished while individual links of the chain pass around the other turret member.

Disposed along the front straight reach of the chain is a wrapper blank fabricating mechanism which produces individual wrapper blanks, having novel easy-opening features, from continuous rolls of wrapper material and which applies a blank to each link of the chain in a position to cover the mold defined thereby. Thus, as each link subsequently arrives at the product-forming stage of the chain travel, the wrapper blank is applied to the product concomitantly with the molding of the product into the patty form, and by the same means. In this manner there is performed at one and the same time and in one operation procedures which in prior machines of this character have required two or more distinct and separate processing steps, thereby giving rise to a more simplified and higher speed packaging operation than has heretofore been possible.

Disposed along the rear straight reach of the chain ex-

2

tending between the two turret members is novel wrapping mechanism for folding down the edges of the wrapper blank in preparation for the sealing operation, the wrapping mechanism being specially designed for operating on a continuously moving package and for assuring that a predetermined edge of the wrapper blank is the last edge to be folded down for facilitating the easy opening of the sealed package as will hereinafter become apparent.

It is therefore an object of this invention to improve upon an apparatus and method for forming a product, supplied in bulk form, into a desired shape and applying a contour wrapper thereto.

It is a further object of this invention to provide an improved apparatus and process for fabricating wrapper blanks from rolls of wrapper material, forming a product into a desired shape for wrapping and applying a wrapper blank to said formed product as a contour wrapper in a continuous, high speed and fully automatic manner.

It is a further object of the invention to provide an improved apparatus and process for fabricating a wrapper blank having easy opening features.

It is a further object of the invention to provide an improved apparatus and process for folding down the edges of the wrapper blank so as to render it a contour wrapper for the contained product.

Further objects of the invention, together with the features contributing thereto and the advantages accruing therefrom will be apparent from the following description when read in conjunction with the drawing wherein:

30 FIG. 1 is a front elevation of the machine;

FIG. 2 is a layout depicting the contour of the camming means associated with the product forming members in relation to the plane of the associated product forming chain throughout the course of the chain's path of travel;

35 FIG. 3 is a plan view of the machine;

FIG. 4 is a plan view in enlarged scale of one of the links of the product forming chain;

FIG. 5 is an end view in elevation of the chain link shown in FIG. 4;

40 FIG. 6 is a sectional view taken along the lines 6—6 of FIG. 4 and including portions of adjacent links of said chain;

FIG. 7 is a view in front elevation of the wrapper fabricating mechanism;

45 FIG. 8 is a detailed view partly in section of a portion of the wrapper fabricating mechanism;

FIG. 9 is a detailed sectional view of the wrapper slitting means and pull tab applicator means taken along the line 9—9 of FIG. 8;

FIG. 20 is a sectional view through the wrapper edge folding mechanism taken along the line 20—20 of FIG. 19;

FIG. 21 is a plan view of the wrapper edge folding mechanism shown in FIGS. 19 and 20;

FIG. 22 is a detailed sectional view in enlarged scale of fold retaining mechanism taken along the line 22—22 of FIG. 21;

FIG. 23 is a plan view of the wrapper sealing turret with the cover removed;

FIG. 24 is a sectional view through the wrapper sealing turret taken along the line 24—24 of FIG. 23;

FIG. 25 is a perspective view of the package ejecting mechanism;

FIG. 26 is a plan view of the package ejecting mechanism;

FIG. 27 is a perspective view of the wrapper blank showing the two laminations thereof in exploded relation to one another;

FIG. 28 is a view of the patty formed product with the wrapper blank partly enveloping same;

FIG. 29 is a view similar to FIG. 28, but with the trailing edge end corners folded down against the product;

FIG. 30 is a view similar to FIG. 29 showing all but the leading edge of the wrapper blank folded against the product;

FIG. 31 is a view similar to FIG. 30 showing all edges and corners of the wrapper blank folded down against the product;

FIG. 32 is a perspective view of the wrapped product inverted from the position shown in FIG. 31;

FIG. 33 is a sectional view in enlarged scale to the wrapper blank taken along the line 33—33 of FIG. 27;

FIG. 34 is an operational view in front elevation showing application of the wrapper blank to a link of the product forming chain;

FIG. 35 is an operational view at a further stage in the chain circuit illustrating the volumetric measuring of the product to be formed and wrapped;

FIG. 36 is an operational view in a still further stage of the chain circuit illustrating the molding of the product and the concomitant partial application of the wrapper thereto;

FIG. 37 is an operational view at a slightly later stage than FIG. 36, illustrating the sharp definition of the edges of the shaped or molded product;

FIG. 38 is an operational view in elevation of a still further stage of the chain circuit illustrating the operation of the trailing edge and trailing corner fold-down mechanism;

FIG. 39 is an operational view in elevation of the parts shown in FIG. 38 at a slightly later stage in the chain circuit and illustrating the overrunning of the trailing edge and corner fold-down means relative to the travel of the chain link;

FIG. 40 is an operational view in plan illustrating the operation of the trailing edge and trailing corners fold-down means in conjunction with the fold-holding mechanism;

FIG. 41 is an operational view in plan at a slightly later stage in the chain circuit illustrating the operation of the fold-holding means, together with the leading edge and leading corner fold-down mechanism;

FIG. 42 is an operational view in elevation illustrating the operation of the leading edge retaining mechanism.

GENERAL ORGANIZATION

Referring now in particular to FIGS. 1 and 3, the machine can be seen to be supported on a rectangular base 10 comprised of elongated bars 11 joined together by a plurality of cross bars 12 to constitute an open supporting framework for the machine. Suitably supported by the base near one end thereof is an upright cylindrical turret assembly 15 hereinafter referred to as the product forming turret the operating parts of which

are enclosed in a side cover 16 and a lid 17. Suitably supported by the base 10 near the other end thereof is another turret assembly 20 hereinafter referred to as the wrapper sealing turret the operative parts of which are enclosed in a side cover 21 and a lid 22. Each of said turrets includes rotating means which serve as sprocket members, hereinafter to be more fully described, cooperating with an endless conveyor chain 25 which extends between and around the outer half periphery of each turret in a substantially elliptical path. The chain is formed of interconnected individual links 26 each formed to define product forming mold as hereinafter more fully described. A product supply chute delivers the loose product to be packaged to the front side of the turret 15 by gravity feed from a supply source, not shown. An excess product collector 28 and an associated screw conveyor 29 serve to return the excess product to the product supply for reuse to thereby avoid product waste.

20 Disposed over the front reach of the chain 25 is an assembly 30 constituting a wrapper blank fabricating mechanism mounted on a frame panel 31. The wrapper fabricating mechanism, as hereinafter more fully described, operates to produce a 2-ply wrapper blank from 33 or 33a and apply an individual wrapper blank to the upper surface of each chain link while passing thereto in the direction of the product forming turret 15. Disposed over the rear reach of the conveyor chain is an assembly 35 constituting a wrapper mechanism for folding 25 down the edges of the wrapper blank over the product carried by each chain link as each link progresses towards the wrapper sealing turret 20. A package ejecting mechanism 40 is disposed over the front reach of the conveyor chain 25 alongside the wrapper fabricating assembly 30 to sweep 30 the finished packages off the conveyor chain as they are 35 delivered from the wrapper sealing turret 20.

All of the aforementioned assemblies are driven from a common power source comprised of a motor 45 suitably mounted on the machine base 10 and which is operatively coupled to a reduction gear box 46 the output shaft of which carries drive chain sprockets 47, 48. Chain means 49 engaging sprocket 47 drives the rotating members of the product forming turret 15 which in turn drives the conveyor chain 25 along with the rotating members of 45 the wrapper sealing turret 20. Chain means 50 engaging with the sprocket 48 serves to drive the wrapper blank fabricating mechanism 30, the package ejector 40 and the wrapping mechanism 35.

The parts of the wrapper blank fabricating mechanism 50 are shown in greater detail in FIGS. 7-13. This mechanism operates to produce the wrapper blank 55 shown in FIGS. 27 and 33 and comprised of a rectangular section of the sheet material 32 superimposed and joined to a rectangular section of the wrapper sheet material 33. A 55 more complete description of the wrapper blank may be had by reference to copending application entitled "Contour Patty Wrapper" bearing Ser. No. 306,573 and filed Sept. 4, 1963. The upper sheet 32 of the wrapper blank is folded over upon itself in a double reverse fold to constitute a pleat 56 running longitudinally of the blank and constituting a tear strip for enabling easy opening of the resultant wrapper. Secured to one end of the pleat or tear strip 56 is a short length of tape 57 of a color distinct from that of sheets 32, 33 and serving as a pull tab for 60 facilitating grasping of the strip. Adjacent to the sides of the pull tab are slits 58 cut in both sheets 32, 33 of the wrapper blank to start and direct the line of tear when the tear strip is pulled to open the wrapper. Edge 61 and adjacent corners 62, 63 may be considered the leading 65 edge and corners, respectively, of the wrapper lamination 32, and edge 64 with adjacent corners 65, 66 may be considered the trailing edge and corners respectively. Edges 67, 68 are the side edges thereof. Similarly, edge 71 and adjacent corners 72, 73 may be considered the leading edge and corners respectively of the wrapper lamination 75

33 with edge 74 and adjacent corners 75, 76 being considered the trailing edge and corners respectively. Edges 77, 78 are the side edges of the wrapper lamination 33.

The sheet material 32, 33 from which the wrapper blank laminations are made is in the present instance a transparent plastic material such as cellophane or the like and is coated on each side thereof with a thermoplastic substance, such as Saran or the like, which in addition to rendering the blank a better air and moisture barrier also enables the two laminations to be joined together and corners thereof to be sealed one upon another under application of suitable heat and pressure. The two laminations of the wrapper blank are joined together within the area of the pleat 56 by means hereinafter to be described. As can be seen in FIG. 33, the joined surfaces of the lamination do not embrace the entire width of the pleat 56 but only the intermediate area lying between the folds which define edges of the pleat so as to avoid application of heat and pressure to the folded edges of the pleat. Application of heat and pressure to the folded edges of the pleat would cause them to be sharply creased and flattened out, thereby altering the crystalline structure thereof in a way that would impair their tensile strength. By limiting the application of heat and pressure to the area between the folded edges defining the pleat, said edges retain their tensile strength to provide improved tearing action along well defined tear lines when the tear strip is severed from the resultant wrapper upon the opening thereof. The two laminations of sheet material 32, 33 comprising the wrapper blank 55 are also joined together at discrete locations 79 along their leading and trailing edges and near to their side edges. This additional joining of the wrapper laminations serves to prevent separation thereof by air currents as the wrapper blank is transported through a succession of operating stages of the machine as hereinafter to be described.

Referring now to FIG. 7, it will be seen that the sheet material 32 is supplied from a roll thereof carried on a spool 81 mounted on a spindle 82, the spool being wider than the sheet material so as to provide a braking surface 40 cooperating with a braking device for maintaining proper tension in the web material as it is being fed through the mechanism. The braking device includes a brake lever 83 carrying a brake shoe 84. Said brake lever has a pivotal connection 85 with the frame panel 31 and is biased in a counterclockwise direction by a spring 86 to cause the brake shoe 84 to frictionally engage the spool 81. The sheet material 32 in leaving the roll feeds over a dancer roller or pulley 87 carried on the end of a bent arm 88 secured to a rotatable shaft 89 suitably mounted in the frame panel 31 and carrying a pin 91 and an eccentrically mounted cam 92. A spring 93 connected to the pin 91 biases the shaft 89 in a clockwise direction which in turn yieldably forces the dancer roll upwardly to take up any slack in the sheet material being fed. The cam 92 serves as a limit for the brake lever 83 and thereby correspondingly adjusts the frictional force applied to the spool 81. The arrangement serves to maintain a substantially constant tension in the web material as it is being fed through the wrapper blank fabricating mechanism. An identical braking device is provided for the roll of web material 33 which includes a brake lever 94, pivot 95, spring 96, the sheet material 33 feeding over a dancer roll 97 supported by arm 98 carried by shaft 99, the shaft carrying a pin 101 and an eccentric cam 102 and being biased in this instance in a counterclockwise direction by a spring 103. The rolls of sheet material 32a, 33a are identical to sheet material 32, 33, respectively, and are provided as standby rolls to be placed in use when their counterparts have been exhausted. Similar braking devices are provided for the standby rolls, the parts thereof being designated by the same reference numerals followed by the suffix "a". Accordingly, it should be understood that reference herein to the processing of sheet material 32, 33 will apply equally as well to their counterpart sheet materials 32a, 75

33a, respectively, since these counterparts are intended to be used alternatively in the mechanism to be hereinafter described.

The web or sheet 32 feeds from the dancer roll 87 around an idler 105 and then to a pleat forming device, see also FIG. 12, comprised of plates 107, 108 having oblique overlapping fold forming edges 109, 110, respectively, for forming the longitudinally running pleat 56. The underlying plate 108 has an angular flange by which the plate is bolted to the frame panel 31. The overlying plate 107 is mounted on a support plate 111 which is similarly bolted to the frame panel 31, the mounting of the plate 107 including a bolt 112 and slot 113 connection for enabling lateral adjustment of the plate 107 for varying the width of the pleat 56. From the pleat forming device the sheet 32 feeds over the idlers 115, 116 to another idler 117.

The sheet 33 feeds from the dancer roll 97 around idlers 118, 119 to the idler 117 where the paths of the two sheets 32, 33 converge and whereafter the two sheets are fed in overlapping relationship over a common feed path throughout the further stages of the wrapper blank fabricating mechanism. From the idler 117 the two sheets run in superimposed relation around an idler 121 25 to a heated roller 120 which operates to join the two sheets together by heat sealing along the area of the pleat 56 formed in the sheet 32 and at the same time securing thereto by heat sealing a short section of tape 57 to serve as a pull tab as heretofore mentioned, the pull tab being applied at spaced longitudinal increments according to the length of individual wrapper blanks.

The tape 57 from which the pull tab is formed is supplied by a reel 122, see also FIG. 8, from which it is drawn through an adjustable spring loaded tensioning device 123 by a tab measuring roller 125 carried by a driving shaft 126, the roller 125 acting in cooperation with a spring biased pressure roller 127 carried by a pivotal arm 128 to continually advance the tape through a tape guide 129 which directs the tape between a pair of cooperating tab cut off rollers 130, 135. Roller 130 is mounted on a shaft 131 and carries an insert block 132 which includes a knife edge 133. Roller 135 is carried by a hollow shaft 136 rotating about a fixed spindle 137 which is cut away along a line substantially corresponding to its diameter to provide a vacuum conduit running to a vacuum pump, not shown. Roller 135 carries two diametrically opposed inserts 141, each being heated and including a hard metal anvil 142, a pair of slitters 143 and a vacuum conduit 144, each vacuum conduit 144 terminating in a vacuum port 145 and communicating with a vacuum conduit 146 extending through the roller 135 and shaft 136 so as to communicate with vacuum conduit 138 during each half revolution of the roller. It will be noted that the surfaces of rollers 130, 135 are spaced apart to allow for the continual feeding therebetween of the tape 57. The outer surface of the inserts 141 is slightly raised so as to bring the anvil into cutting contact with the knife edge 133 to cut off a length of tape 57 to be applied to the wrapper blank as a pull tab. 50 Roller 135 is driven at one half the speed but at the same surface velocity as roller 130 so that at each half revolution of roller 135, a length of the tape will be cut off at a time in which the vacuum port 145 is communicating with the vacuum conduit 138 so as to hold the cut off length of tape to the surface of insert 141 for approximately one half revolution of the roller.

The tape 57 is a thermo-stable substance, such as paper or the like, coated on one side with a layer of thermoplastic material, such as Saran or the like; the thermoplastic coating being on the surface opposite to the surface in contact with the insert 141. The use of the term thermo-stable herein is intended to define material which does not become plastic upon application of heat. The cut off length of tape is then carried by an insert from the point of cut off to a point where the tab is carried

into contact with the feeding sheet 32, at which point the vacuum port 145 is cut off from the vacuum conduit 138. While it is being transported, the thermoplastic coating on the tape becomes heated so that when the tab is brought into contact with the sheet 32 and the vacuum holding it to the insert is cut off, the tab will adhere to the sheet 32 at a location overlying the pleat therein. At the same time the slitters 143 cut through the two sheets 32, 33 to form the slits 58 running alongside each side of the pull tab as heretofore described.

The heat sealing roller 120, as best seen in FIG. 11, is contained in an assembly which includes a heating disc 148 and insulator discs 149, the assembly being mounted on a driven shaft 151 supported by a bearing sleeve 152. The sleeve 152 is supported by a pair of rock arms 153 carried by a sleeve 154 loosely mounted on a driven shaft 155. A pin 156 extending between the two arms 153 is pivotally joined to the plunger 157 of a pneumatic actuator 158 suitably secured to the frame panel 31. Mounted on the inner arm 153 and disposed on the inner side of the frame panel 31 is a brush assembly 161 cooperating with a collector ring assembly 162 carried by shaft 151 for completing a circuit to heating elements contained within the heating disc 148. Disposed on each side of the heat sealing roller 120 is a sheet guide 164 carried by a rock shaft 165, each guide being curved through an arc concentric with the roller 120 for supporting the sheets during the heat sealing operation, the upper ends of said guides 164 being adapted to bear on the rock arms 153. Cooperating with the heat sealing roller is a backup roller 168 carried by a driven shaft 170. The pressure exerted on the sheet material by the heat sealing roller 120 and backup roller 170 acts to seal together the folds comprising the pleat in sheet 32 and joining sheet 32 with sheet 33, which sheets have been heated upon making contact with the roller 120, the pressure also serving to firmly join the pull tab 57 to the pleat, it being noted that the pressure is applied to the area of the pleat intermediate the edges of the pleat for reasons heretofore mentioned. Means, not shown, are provided for operating the pneumatic actuator 158 whenever the mechanism is shut down, so as to prevent over-heating of the sheet in contact with the roller 120, said actuator when operated causing the support arms 153 to rock downwardly and lower the roller 120, the sheet guide 164 at the same time rocking in a counterclockwise direction and serving to hold the sheet out of contact with the heated roller 120, the backup roller 168 and also the heated insert 141 of roller 135 while the mechanism remains shut down.

From the heat sealing roller 120 the two sheets 32, 33 are drawn about an edge sealing roller 169 mounted on a driven shaft 170, see also FIG. 10. Roller 169 carries near each end thereof a raised insert 171 which is heated. Cooperating with the roller 169 is a pressure roller 174 carried by a shaft 175 mounted in vertically slidable bearing blocks 176 adapted to slide in suitable cut outs in the framework under control of a manually actuatable eccentric cam 177. Roller 174 coacts with the inserts 171 of roller 169 so as to apply pressure to the sheets 32, 33 and thus seal together the sheets at areas which will constitute edges of the resultant wrapper blanks as hereinafter more fully described.

From the edge sealing rolls the sheets 32, 33 run about a measuring roll 184 carried by a driven shaft 185. Cooperating with the measuring roll 184 is a pressure roll 188 mounted on a driven shaft 190. The surface of the measuring roll 184 is preferably knurled, and the surface of the pressure roll 188 is formed of resilient material such as polyurethane or the like. The two rolls firmly grip the sheet material and serve as the means for withdrawing the sheets 32, 33 from their supply spools for delivering same to means for cutting off the sheets in precisely measured lengths to constitute a wrapper blank. The cut off means include a roller 192, see also FIG. 18,

mounted on a shaft 193 carried in bearing blocks 194 which are spring loaded, the roll having a knife edge insert 195. Cooperating with the cut off roll 192 is an anvil roll 198 carried on a driven shaft 200. Rolls 192, 198 allow for free passage of the sheets 32, 33 therebetween as delivered by the measuring roll 184, the sheets being severed when the knife edge is rotated into engagement with the anvil surface of the roll 198. As can be seen by reference to FIG. 18, the knife edge insert 195 registers with the sheets 32, 33 so as to sever the sheets along a transverse line coinciding substantially with the leading edge of the pull tab 57. The cut made by the knife edge 195 is not continuous but is interrupted at two discrete locations to leave two narrow uncut portions 202 which are subsequently torn and which temporarily prevent the severed edge of the sheet material from adhering to the cut off roll.

From the cut off roll the sheet material runs between an applicator roll 204 carried by shaft 205 and a pair of laterally spaced snapper rollers 206, there being suitable guides for the sheet material, not shown, only one of the snapper rollers 206 being shown in FIG. 7. The surface of the applicator roll 204 is of a resilient substance, such as polyurethane or the like, which is in bearing contact with the upper surface of the conveyor chain links 26 so as to be driven by the conveyor chain 25, the applicator roll 204 serving to apply or iron down a wrapper blank on the surface of each link. The velocity of the conveyor 25 is slightly greater than that of the sheet feed through the fabricating mechanism as determined by the measuring roll 184 with the result that when the almost completely severed wrapper blank is accelerated by the applicator roll and snapper rollers 206, the narrow interconnecting portions 202 are torn so as to completely sever the leading section of the sheet material constituting a single wrapper blank.

The means for driving the various driven rolls of the wrapper blank fabricating mechanism is shown in FIG. 13, the source of power being derived from the roller chain 50 which reaches around a chain sprocket 210 to drive through shaft 211 a bevel gear 212. The gear 212 meshes with a bevel gear 213 on a shaft 214 which also carries a gear 215. The gear 215 drives through idler gears 216, 217 and 218 a gear train comprised of gears 220, 221, 222, 223, 224, 225 and 226, of which train gears 222 and 225 are idlers. Gears 220, 221 are mounted on shafts 193, 200, respectively, for driving the cooperating cut off rolls 192, 198. Gears 224, 223 are mounted on shafts 190, 185, respectively for driving the cooperating sheet measuring rolls 188, 184 respectively. Gear 226 is mounted on shaft 170 for driving wrapper blank edge sealing roll 169. Shaft 200 also carries a pulley 228 around which is wrapped a drive belt 230. Drive belt 230 extends around a pulley 231 mounted on shaft 155, 55 thence around pulley 232 mounted on shaft 131, thence around an idler pulley 233 and back to the pulley 228. Shaft 131 carries the pull tab cut off knife roll 130. A drive belt 235 stretched between a pulley 236 on shaft 155 and a pulley 237 on shaft 151 drives the heat sealing roller 220 which shaft, in this view, is shown in its operative position. A gear 240 mounted on shaft 131 meshes with a gear 241 integral with a pulley 242 around which is wrapped a drive belt 243. Belt 243 runs around idler pulleys 244, 245 and 246 to engage a pulley 247 mounted on shaft 136, the belt 243 thence returning over an idler, not shown, loosely mounted on shaft 131 to the pulley 242. The shaft 136 to which pulley 247 is secured drives the pull tab cut off anvil roller 135. Shaft 136 also carries a sprocket 248 which drives a roller chain 249 stretched around a sprocket 251 secured to shaft 126, said shaft 126 carrying and driving the pull tab tape measuring roller 125. From the foregoing it will be apparent that the wrapper fabricating mechanism operates continually to withdraw sheet material 32, 33 from the supply rolls thereof, forms a pleat in sheet 32, seals the two sheets

together along the area of the pleat while at the same time applying a length of tape thereto to serve as a pull tab, seals the two sheets of material together in locations which become the edges of the wrapper blank, cuts off precisely measured lengths of the sheet material to constitute individual and separate wrapper blanks, and applies a blank to each link 26 of the chain conveyor 25.

CONVEYOR CHAIN

The conveyor chain 25 consists of a plurality of connected links 26, each link being formed, as best seen in the detail views FIGS. 4, 5 and 6, of a casting 255 having a raised circular shank 256 to the top surface of which is secured by screws 257 a flat horizontally disposed and substantially rectangular plate 258. The casting is formed with a circular vertical bore to which is fitted an insert 259, the inner surface of which defines a cylindrical cavity or mold for forming a cylindrical patty as hereinafter to be more fully described. A corresponding circular opening is formed in the plate 258, the inner surface of which lies flush with that of the insert 259. The casting 255 is formed with a tapered extension 261 having a vertical bore to which is fitted a bearing 262. The casting at the opposite end is bifurcated to form two spaced apart extensions 264 each of which is fitted with an insert bearing 265. The extension 261 of one casting is adapted to fit between the spaced apart extensions 264 of the adjacent casting, the two castings being pivotally coupled to one another by a pin 266. It will be noted that the leading and trailing edges of the plate 258 taper inwardly from their center point, and this provides clearance between the plates of adjacent links as the conveyor traverses an accurate path around the turrets 15, 20 in a manner hereinafter to be more fully described. Recessed into the upper surface of plate 258 along its leading edge are two discs formed of a substance having a natural affinity for the material of which the wrapper blank is formed, said discs being made of polyvinyl chloride or the like which tends to adhere to the Saran coating of the wrapper blank and thus serve to frictionally retain the wrapper blank on the plate 258 as it travels towards the product forming turret 15. The several links 26 formed as above described comprise the endless conveyor chain 25 cooperating with sprocket members forming part of the product forming turret 15 and part of the wrapper sealing turret 20, each link as it leaves the applicator roll 204 of the wrapper blank fabricating mechanism 30 carrying with it a wrapper blank, not shown in FIGS. 4, 5 and 6, resting on the plate 258 and overlying the cylindrical cavity or mold of each link in preparation for receiving a charge of product to be molded, wrapped and sealed within the wrapper at the later stages of the conveyor chain route.

PRODUCT FORMING TURRET

Details of the product forming turret 15 and parts associated therewith are best seen in FIGS. 14, 15, 16 and 17. Referring now to FIG. 17, the product forming turret comprises a rotating assembly and a stationary assembly supported by an upright shaft 270 suitably mounted in the base framework of the machine and supported at its lower extremities by a stationary sleeve 271. The rotating assembly of the turret is carried by a sleeve 272 rotatably mounted on the shaft 270 by means of ball bearings 273, 274 and 275, said sleeve having secured thereto lateral flanges 276, 277 and 278. Bolted to the lower flange 276 are a pair of drive sprockets 280 driven by dual drive chains 49, see FIG. 1. Bolted to the flanges 277, 278 is a weldment which includes an inner wall 282, a laterally disposed disc 283 and an outer wall 284 to the upper end of which is joined an outwardly projected shelf 285, the said parts of the weldment being suitably braced to provide an integral rigid structure. Bolted to a spacing ring 286 underlying the disc 283 are a series of plates 287, see FIG. 14, the outer edge of which are serrated with spaced

semicircular recesses 287 so as to define intervening sprocket teeth 288, the recessed surfaces 287 being adapted to accommodate the circular shank formed in each link 26 of the conveyor chain and serving to render the disc 283 in effect a sprocket wheel for driving the conveyor chain 25.

Also supported by the disc 283 is a flat annular plate 290 into which is fitted a cylindrical open cup 291, the upper edge of which is flush with the surface of the plate 290, the lower edge of which is spaced slightly above the surface of the plate 258 forming part of each conveyor chain link 26. The cup 291 has the same internal dimensions as those of the cavity or mold in the conveyor chain links 26, the cups being mounted in vertical alignment with the cylindrical cavities in the links, the cups serving as a volumetric measuring means for the product to be molded into a patty as hereinafter described. The flat plate 290 serves as a fill table upon which the loose product to be formed and wrapped is deposited, and in so doing 20 filling up the measuring cup 291.

Secured to the outwardly extending shelf 285 of the rotating weldment structure is a supporting sleeve 295 around the inner surface of which is fitted a bearing 296 for guiding a vertically slidable shaft 297 carrying at its 25 bottom end a conical shaped plunger 298, there being one such plunger for each measuring cup 291, it being vertically aligned therewith, the maximum outer dimensions of the plunger being slightly less than the interior dimensions of the associated cup 291. Rising upwardly from the shelf 30 285 near its outer edge is a wall 299.

The stationary portion of the turret structure comprises a weldment including an outer circular wall 301 joined to a horizontally disposed disc 302 in turn secured to a sleeve 303 supported from the upper portion of the shaft 270. 35 The structure is suitably braced to give it adequate strength and rigidity. Secured to the outer surface of the wall 301 are a pair of spaced apart rails 305 which serve as a cam track and accommodate between them a follower roller 306 secured to the upper portion of the ram shaft 297.

40 The rails 305 control the vertical motion of the ram 298 as the rotating portion of the turret mounted on the sleeve 272 rotates relative to the stationary turret structure including wall 301 supported from the stationary sleeve 303. The ram in FIG. 17 is shown in its most elevated position, which is the position it assumes during the filling and measuring stage prior to being actuated downwardly to form the product in a manner to be hereinafter 45 more fully described. The extreme upper portion of each ram shaft 297 is bifurcated to receive a link 308 connecting each shaft with an adjacent shaft 297 as can also be seen in FIG. 16, the links being slotted to receive a threaded pin 309 which pivotally joins the links at each end thereof to a ram shaft 297. The links 308 are in this 50 manner connected to adjacent shafts 297 in pairs, to prevent the shafts from rotating about their longitudinal axis and thus maintain the follower rollers 306 in engagement with the cam track defined by the rails 305.

55 As can be seen also in FIG. 17, each link 26 of the product forming conveyor chain carries a piston 311 slidably fitted within the cylindrical cavity or mold of each chain link. The piston is formed with an extended block 312 made of material having a low coefficient of friction and formed with a convex bottom surface adapted to ride along a cam rail or track 313 supported on threaded studs 314 locked in an adjusted elevation to a horizontally disposed frame table 315 which constitutes part of the framework of the machine and extends around the entire machine in underlying relation to the product forming chain comprised of the links 26. The elevation of the rail 313 is 60 adjusted at various heights at different stages of the chain's travel and thereby controls the rise and fall of the piston 311, which may be considered a false bottom for the cylindrical mold of each chain link, depending upon the operation to be performed. The chain link 26 is shown in FIG. 75 17 as being supported on its inner side by the sprocket

defining plate 287. The outer edge of each link 26 is supported by an assembly of support and guide bars 316 secured to the table 315 and arranged to present an inwardly disposed step in which is seated the outer bottom corner of the casting 255 comprising a portion of chain link 26. The guide bar assembly 316 runs completely around the machine in register with the chain path of travel so as to guide and support the links 26 throughout the entire endless circuit of the chain.

FIG. 15 is a perspective view of a portion of the product forming turret 15 at the product receiving location thereof. As will be seen in FIG. 15, at this location the rams 298 are at their most elevated position. At this location the product, not shown in this view, to be formed and wrapped, is delivered from the chute 27 in a relatively steady stream on to the fill table 290, the product being delivered in sufficient quantity to at least fill each volumetric measuring cup 291 as it is rotated past the fill station. At this point there is a wrapper blank, not shown in FIG. 15, overlying each plate 258 of an associated conveyor chain link and at which location the piston, not shown in FIG. 15, carried by each link is at an elevated position where its upper surface is flush with the surface of the chain link plate 258, thereby in effect providing a bottom for the measuring cup which becomes filled with the product. In order to prevent the loose product from spilling over the edge of the fill table, a retaining wall 321 is provided near the outer edge of the fill table, said wall being supported on a suitably mounted bracket 322, which bracket also carries a depending flap 323, partly broken away, for retaining the product within the fill station. The fill station is located just beyond the beginning point of tangency of the product forming chain 25 with the product forming turret 15.

FIG. 16 is a perspective view of a portion of the product forming turret extending from a point about 90° advanced from the beginning point of tangency to a point near the ending or exit point of tangency of the product forming conveyor chain. At a point about 90° around the turret from the beginning point of chain tangency is a station which may be referred to as a measuring station whereat is located a scraper plate 325 overlying the fill table 290 and extending along a chordal line in relation thereto. The bottom surface of the scraper plate 325 acts as a plow to divert excess product lying on the surface of the fill table into the product return chute 28 which delivers the excess to the associated product return screw conveyor 29. Disposed slightly beyond the scraper plate 25 is a rotating brush 326, the axis of which also extends chordally across the fill table, the brush 326 serving to sweep clean the surface of the fill table while providing an accurate volumetric measuring of the product contained within each measuring cup 291. The brush 326 is supported by blocks 327 mounted on legs 328 adjustably secured to a mounting shelf 329 in such a manner as to enable the elevation of the brush 326 to be adjusted for determining the amount of product which will be retained within each measuring cup 291. The brush is driven by a flexible shaft 330 coupled in any suitable manner to the motor 45. As the turret continues to rotate beyond the measuring station, whereat brush 326 is located, the cam track 305 starts to incline downwardly rather sharply to drive the rams 298 downwardly. The rams while being driven downwardly enter the volumetric fill cups 291 and displace the measured charge of product contained therein downwardly into the product forming cavity or mold formed in the associated chain conveyor link 26 and at the same time forcing the wrapper blank underlying the measured charge of product into the mold of the conveyor link. By this time the false bottom piston 316 for the mold has been lowered so as to allow for the entry of the charge into the mold, the charge being compressed within the mold between the piston and the ram so as to assume the form of a cylindrical patty. While the ram is still at its lowermost position and at a slightly later stage

in the rotation of the turret, the piston is slightly elevated to provide a compressive force on the patty from below for the purpose of providing a sharply defined bottom edge for the patty which would not result except for the slight elevation of the piston.

FIG. 2 illustrates the contour of the cam track 305 and cam rail 313 for controlling the vertical movements of the rams 298 and pistons 311 respectively. The starting point for the diagram is at the point of chain travel where a wrapper blank is applied to a chain link by the wrapper blank fabricating mechanism 30. At the beginning point of the diagram, the line indicating the cam track 305 is shown broken because at this time the rams are not disposed in cooperative relation to their respective links of the chain and do not become aligned with their respective links until the link arrives at the beginning point of tangency relative to the turret 15. During this period the cam track 305 operates to retain the ram in its uppermost position, and the piston carried by the link is likewise retained in an elevated position leading up to the beginning point of tangency. Shortly before 90° after the start of tangency, the cam track 305 slopes sharply downward to reach full bottom position at about 140°. During this same time period the cam rail 313 slopes downwardly to reach full bottom position also at about 140°. At about 150°, cam rail 313 rises slightly to cause a sharper definition of the bottom edge of the patty as heretofore mentioned. Shortly before 180° from the beginning point of tangency, which is the ending point of tangency of the chain relative to the turret, cam track 305 slopes upwardly to return each ram to its uppermost position. At about the ending point of tangency, the cam rail 313 starts a gradual rise for elevating the respective piston so as to raise the patty formed product to a proper elevation for the wrapper edge folding mechanism as will hereinafter be described. It should of course be understood that while the charge of product is being compressed within the mold of a chain link 26 by the co-active forces exerted by a piston 311 and a ram 298, a wrapper blank is being partly applied to the formed patty, the wrapper blank underlying the patty and being folded around the sides of the patty so that as the ram starts to rise and the patty is carried away from the product forming turret, the edges and corners of the wrapper blank project upwardly above the surface of the conveyor chain link 26 as the patty is advanced towards the wrapping mechanism 35 which operates to fold down the upstanding edges and corners of the wrapper blank on the top surfaces of the patty in an iris form of wrap 50 in a manner next to be described.

WRAPPING MECHANISM

The wrapping mechanism 35 for folding down the upstanding edges and corners of the wrapper blank after the product has been formed is illustrated in FIGS. 19-22, the mechanism being driven from the motor 45 and gear box 46 through the dual roller drive chains 50 which reach around dual sprockets 335 carried at the lower end of an upright shaft 336 journaled in a bearing block 337 mounted in the frame table 315. Shaft 336 carries a sprocket 340 around which is wrapped a chain 341 running to a sprocket 342 carried at the lower end of a shaft 343. Shaft 343, as best seen in FIG. 20, is journaled in a bearing block 345 mounted in the frame table 315, the upper end of shaft 343 carrying a bevel gear 346 meshing with a bevel gear 347 on a shaft 348. The chain 341, as can be seen in FIG. 21, in returning to the sprocket 340 passes around an idler sprocket 351 carried at the bottom end of a shaft journaled in a bearing block 352. The shaft 348 drives, through a friction clutch 354, a shaft 355 journaled in a bearing block 356 mounted in an upright frame panel 357. The outer end of shaft 355 carries dual sprockets 358 around which is drawn dual roller chains 360. The chains 360 reach around an idler sprocket 361, as best seen in FIG. 19, and thence around

another idler sprocket 362 returning over a lower reach of the chain to the drive sprocket 358 along which lower reach they also mesh with small idler sprockets 363, 364. All of said idler sprockets 361-364 are suitably mounted in the upright frame panel 357. Secured to the chain at regular spaced apart intervals are a plurality of wrapper edge fold down devices, each device consisting of trailing edge fold down finger 366 and a tapered yoke shaped shoe 367 for gathering in and folding down the trailing corners of the wrapper blank. The devices comprised of the finger 366 and shoe 367 are spaced apart on the chain 360 at distances corresponding to the length of each conveyor chain link 26, and the chain 360 is driven at a velocity slightly greater than that of the conveyor chain comprised of the links 26. Accordingly, as the devices traverse the lower reach of chain 360 they slightly overrun the patty and wrapper blank carried by each conveyor chain link 26 and in so doing the finger 366 operates to fold down the trailing edge of the upstanding wrapper blank as the yoke shaped shoe 367 gathers in the trailing corners of the wrapper blank to fold them down with the trailing edge in overlapping relationship on the upper surface of the patty. Cooperating with the fold down devices are fold retaining means, next to be described, which serve to temporarily hold the trailing edge and corners folded down after each fingers 366 and shoe 367 arrive at the end of the lower reach of chain 360 and are elevated away from the patty as they ride around the sprocket 358.

The hold down means include a dual roller chain 370 driven from dual sprockets 371 carried by the upper end of the shaft 336, the chains 371 running around idler sprockets 372 carried by a shaft journaled in a bearing block 374 mounted in the frame table 315. Pivots connected to the links of chain 370 by pivot pins 373, see FIG. 22, at spaced intervals along the chain is one end of an arm 375 which at its other end carries a conical shaped roller 376 fastened to the arm by a pin 380. The roller 376 rides in a V-shaped cam track defined by the bevelled edges of plates 377, 378 both of which plates are secured to a supporting plate 379. Secured firm to the arm 375 is an outwardly projecting blade 381, the blade 381 and arm 375 constituting a form of bell-crank lever actuatable about two separate pivot axes. In FIG. 21 the line 382 indicates the path of the cam track guiding roller 376. It will be noted that on the inner reach of the chain 370 the cam track 382 runs parallel with the path of chain 370. However, on the outer reach of the chain the cam track 382 departs from parallel relation to the path of chain 370 as it leaves the sprocket 371 and as it approaches the sprocket 372, the cam track 382 coinciding with the chain path over a portion of the outer reach of the chains. This diversion between the path of the cam track and that of the chain serves to articulate the blade 381 in a manner to project it outwardly in a straight line transverse to the path of conveyor chain links 26 to a position where it overlies and holds down the edges and corners of the wrapper blank folded down by the finger 366 and shoe 367. The hold down blade 381, being driven at the same speed as the conveyor chain links 26, retains the same position until the link 26 reaches the leading edge and corner hold down means means whereupon the hold down blade 381 is retracted in a direction substantially perpendicular to the direction of travel of the conveyor chain links 26 due to the diverting courses of the cam track 382 and the chain 370 as the blade approaches the sprocket 372.

The leading edge and leading corner fold down means comprises a shell or plow 385 overlying the links 26 of the conveyor chain and formed with inwardly stepped edges 386, 387, which terminate in an elongated slot 388. The edge 386 serves as a plow for folding down the outer leading corner of the wrapper blank with the edge 387 serving the same function relative to the inner leading corner thereof. The leading edge of the wrapper

blank, at least the center portion thereof, is folded down finally when it reaches the end of the elongated slot 388. It will be recalled that the leading edge of the wrapper blank is the edge to which the pull tab 57 is applied, as shown and described with respect to FIG. 27, the pull tab being applied to the pleat 56 which runs along the center line of the wrapper blank. Accordingly, the structure of the shell 385 provides that the pull tab area of the wrapper blank is the last portion of the blank to be folded down, and in overlying relation to the other folds, so as to render the pull tab readily accessible for subsequently opening the wrapper.

In order to assure that the edge of the wrapper blank to which the pull tab is secured is not accidentally folded down prematurely, a retaining device is provided to hold the pull tab section of the leading edge from being folded down before all other edges and corners of the wrapper blank are folded down. This retaining means is driven from a roller chain 390 wrapped around a sprocket 391 on shaft 348 and a sprocket 392 carried on the inner end of a shaft 393. Shaft 393 is suitably journaled in a frame support panel 395 and carries at its outer end dual sprockets 396 around which is wrapped dual chains 397. Chains 397 run around idler sprockets 398, 399 suitably mounted on the panel 395. The chains 397 carry at spaced intervals, corresponding to the pitch of the conveyor chain links 26, a bent over finger 401 mounting a projecting retainer tip 402 which may be made of resilient material such as rubber tubing or the like. The chains 397 are driven at the same speed as the conveyor chain links 26, and as the fingers 401 traverse the lower reach of the chain the retainer tips 402 engage the leading edge of the wrapper blank in the area of the pull tab at the time that the leading corners of the wrapper blank are being folded down by the fold down edges 386, 387 of the shell or plow 385, the tip 402 holding the central leading edge area upright and riding through the slot 388 to give assurance that the pull tab section of the wrapper blank is folded down last to constitute the overlying fold in the iris wrap for the wrapper blank.

As can be noted by reference to FIG. 20, throughout the reach of the conveyor chain between the product forming turret 15 and the wrapper sealing turret 20, means are provided for supporting the inner side of each chain link, said means being similar to the heretofore described means 316 supporting the outer side of the chain links and including an assembly of bars 403 formed to define a step for seating the inner edge of the conveyor link casting 255 thereby serving to guide and support the links of the chain in cooperation with the bar assembly 316 so as to maintain the conveyor chain in accurate alignment and at the required elevation for the cooperative action of the wrapping mechanism hereinafter described.

After the leading edge of the wrapper blank is finally folded down, the folded edges of the wrapper blank are retained in folded position by the shell 385 overlying the links 26 of conveyor chain 25 and extending along the chain path up to the beginning point of tangency thereof with the wrapper sealing turret 20.

WRAPPER SEALING TURRET

The wrapper sealing turret is shown in detail in FIGS. 23 and 24. With reference first to FIG. 24, it will be seen that the turret structure is mounted on an upright shaft 405 suitably secured to the base frame of the machine which includes an upright cylindrical weldment 406 into which the lower portion of shaft 405 is fitted. Rotatably mounted on the upper end of the shaft 405 by means of ball bearings 407, 408 and 409, is a sleeve 411, across the top of which is secured a cap 412 formed with an upright cylindrical extension. Supported by flanges 413, 414 secured to the rotatable sleeve 411, is a weldment which includes a horizontal disc 415 to the outer

edge of which are fastened plates 416 similar to the plates 287 in the product forming turret mechanism, see FIG. 14, having a serrated edge which engages with the chain link castings 255, and constitute sprocket teeth so as to render the disc 415 in effect a sprocket wheel for the chain conveyor 25. The chain conveyor, being driven by the sprocket wheel of the product forming turret 15, drives the sprocket wheel 415 of the wrapper sealing turret to rotate it about the shaft 405.

Also supported by the shaft 405 is a separate weldment including a disc 420 joined to a cylindrical sleeve 421 across the top of which is a cover plate 422. The sleeve 421 is mounted for vertical slide movement on insert bearing blocks 424 attached to sleeve 411. A pair of drive pins 425, one shown in FIG. 24, are mounted in the sprocket disc 415 and extend upwardly through bushings carried by the disc 420, said drive pins serving to rotate the disc 420 in unison with the sprocket disc 415.

Mounted around the outer edge of the disc 420 are a plurality of heated platen assemblies which are spaced apart corresponding to the spacing of individual links 26 of the conveyor chain 25. The platen assembly includes a mounting plate 431, an insulator disc 432, a heating disc 433, and a wrapper sealing platen 434. The assembly is bolted together to form an integral unit and is secured in cut out areas of the disc 420 by means of bolts 435, said bolts being threaded into disc 420 and carrying springs 436 for biasing the assembly in a downward direction against the surface of the disc 420. Each heating disc 433 contains resistance elements which are connected by wires 437 to an electrical temperature control unit 438 which is connected by a cable 439 running to a brush assembly 441 cooperating with a collector ring assembly 442. Said collector ring assembly is mounted on the top portion of the shaft supporting weldment 406 and is connected to a source of electrical power, the brush assembly 441 being secured to the flange 413. The brush and collector ring assemblies 441, 442, are contained within two interfitting cup shaped enclosures 443, 444, the enclosure 444 being secured to the weldment 406 and the enclosure 443, inverted relative to enclosure 444, is secured to the flange 413.

As each link 26 of the conveyor chain 25 reaches the beginning point of tangency relative to the sprocket disc 415, the wrapped package carried by the link will underlie an associated one of the heat sealing platens 434 so that as the conveyor chain link travels about the outer half periphery of the wrapper sealing turret, heat is applied to the folded over edges of the wrapper blank under suitable pressure and for the proper time interval to cause the folded over edges of the wrapper blank to fuse together and thereby enseal the enclosed product. The pressure of the package against the heated platen is determined by the elevation of the cam rail 313 acting on the piston 311. As can be noted with reference to FIG. 2, the cam rail 313 immediately after the beginning point of tangency with the wrapper sealing turret rises slightly so as to press the folded over edges of the wrapper into pressure engagement with the associated heated platen 434. As the respective chain link approaches the ending point of tangency with the wrapper sealing turret, the cam rail 313 drops slightly so that at the time when the conveyor chain and the sprocket start to diverge, the wrapped product will be out of tight pressure engagement with the heated platen. This prevents smearing of the wrapper folds by the heated platen as it continues its circular course away from the chain conveyor. The spring bias provided by the springs 436 is adjustably settable so that the pressure applied by the platen can be accurately regulated.

In order to prevent overheating of the wrapper folds when the machine is stopped, with the wrapper product still on the conveyor chain, means are provided for lifting the platen supporting disc 420 to remove the heat and pressure from each package. The lifting means includes a

gas impervious balloon or bellows member 450 disposed in the space between the upper end of shaft 405 and the cover plate 422 for the sleeve 421, said bellows resting on the upward extension of cap 412. Communicating with the bellows 450 by means of a swivel coupling 451 is a conduit 452 running to a supply of compressed air. Whenever the operation of the machine is stopped, means are provided for connecting said conduit with the compressed air supply which enters the bellows 450 to expand same thereby elevating the sleeve 421 and structure supported thereby, including the platen mounting disc 420. The amount of lifting movement imparted to the disc 420 is limited by limit pins 455 threaded into the sprocket disc 415 and projecting upwardly through the platen supporting disc 420, the enlarged head of each pin 455 limiting the upward movement of the disc 420. As a means for precisely setting the lower limit of platen supporting disc 420, when the compressed air supply is turned off and operation of the machine is to be resumed, there are provided spacer blocks 456 secured to the under side of the platen supporting disc 420 and adapted to bear on the sprocket disc 415 to maintain the two discs 420, 415 in properly spaced relationship. Preferably, the under-surface of each spacer block carries a layer 457 of resilient shock absorbing material for preventing jarring impact as the disc 420 drops downwardly after the compressed air supply is cut off.

PACKAGE EJECTOR MECHANISM

30 Each package carried by a link 26 of the conveyor chain 25 as it leaves the ending point of chain tangency with the wrapper sealing turret is carried by the chain to an ejecting station whereto is located ejector mechanism as shown in FIGS. 25, 26. The ejecting mechanism 35 40 is mounted between frame bars 461, 462, the forward end of which bars supports a rotatable shaft 463, the rear ends of the bars supporting a similar shaft 464. Carried by the shaft 463 are a series of chain sprockets 466, the shaft 464 carrying a series of sprockets 467. A plurality 40 of chains 470 are wrapped around each aligned pair of sprockets 466, 467. Extending between and connected to adjacent pairs of the chains 470 are sweeper bars 471 which are arranged in staggered relation across the three 45 adjacent paths of travel. The sweeper bars 471, when drawn along the lower reach of the chains sweep laterally across the flat plate 258 of each chain link assembly 26 and in so doing engage a package being transported by the chain link 26 and eject it into an associated discharge chute 475 wherein the packages are conveyed to cartoning 50 equipment forming no part of the instant invention. Each sweeper bar 471 is formed with a projecting finger 472 for positively limiting the further travel of the package by the associated conveyor chain link 26. The staggered spacing of the several sweeper bars 471 and the 55 speed of rotation thereof is coordinated with the velocity of the conveyor chain travel so that the sweeper bars of each of the three adjacent channels are effective for ejecting every third package carried by the conveyor chain links 26 and in this manner ejecting all of the finally 60 wrapped and sealed packages into one or the other discharge chutes 475. The ejecting mechanism is driven by a roller chain 477 wrapped around a sprocket 478, said chain being driven through appropriate sprocket and gearing means, not shown, but associated with a drive 65 shaft 480, see FIG. 13, which carries a bevel gear 481 meshing with bevel gear 212, heretofore described, forming part of the means for driving the wrapper blank fabricating mechanism.

As can be seen by reference to FIG. 2, the cam rail 70 313 takes a slight rise just prior to the eject station so as to thereby elevate the package slightly above the plane of the top plate 258 forming part of each link 26 of the conveyor chain. In this manner, assurance is provided that each wrapped package will be completely clear of and 75 above the cavity or mold in the associated chain link 26

so that there will be not obstruction to the ejection of the package from the chain by operation of the sweeper bars 471 heretofore described. Upon leaving the eject station, the cam rail 313 takes a slight drop to bring the associated piston 311 carried by each link of the chain substantially flush with the surface of the top plate 258 of each link in preparation for receiving a wrapper blank therein by the wrapper blank fabricating mechanism to start a new packaging cycle.

SUMMARY OF OPERATION

The following summary of operation of the product forming and wrapping mechanism will be described with particular reference to FIGS. 27 through 42 in addition to FIG. 2. FIG. 34 illustrates the conveyor chain at a point which may be considered the beginning of its endless path, at which point the wrapper blank applying roll 204 is applying a wrapper blank 55 to the flat upper plate 258 of one of the chain links 26. It will be noted that the wrapper blank 55 has been completely separated from the sheet material 32, 33, the detailed construction of the wrapper blank being heretofore described and shown in FIG. 27. At this point of the chain's route it will be noted that the false bottom or floating piston 311 is maintained at an elevation by the cam rail 313 in which the top surface of the piston is substantially flush with the top surface of the plate 258.

FIG. 35 illustrates a later stage in the route of the conveyor chain after the respective chain link 26 has passed through the filling station whereat the product to be formed and wrapped has been spilled on the fill table 290, the position shown being that wherein the product 485 within the associated volumetric measuring cup 291 is being leveled off by the brush 326 to provide an accurate and controlled measure of the product charge in the measuring cup. At a point just prior to the location of the brush 326 an accumulation of excess product 485 is being scraped off the fill table 290. This stage of the operation occurs when the chain link is approaching 90° beyond the beginning point of tangency of the chain with the sprocket associated with the product forming turret.

FIG. 36 illustrates a still further stage in the conveyor chain route wherein the product forming ram 298 has been driven downwardly through the volumetric measuring cup 291 to transfer the measured charge along with the underlying wrapper blank 55 into the cylindrical mold of the chain link 26. It will be noted that at this stage the cam rail 313 has also dropped to lower the piston 311 so as to accommodate the charge of product 485, the ram 298 and piston 311 being indicated at their bottom positions. At this stage the lower edges of the compressed charge of product are rounded off, i.e., the product 485 does not completely fill the interior dimensions of the mold. This stage of operation occurs about 140° after the beginning point of tangency of the conveyor chain with the sprocket wheel associated with the product forming turret.

FIG. 37 illustrates a slightly further advanced stage of the conveyor chain route in which the charge of product 485 has been completely compressed or compacted into its final patty configuration. It will be noted in this view that the cam rail 313 has taken a slight rise to force the piston 311 upwardly which has the effect of squaring off the bottom edges of the formed patty, the action occurring while the ram 298 is still at its full bottom position. This stage of the operation occurs just after 150° beyond the beginning point of chain tangency with the sprocket wheel associated with the product forming turret. At this stage of the operation the wrapper blank 55 has been partially applied to the patty and is substantially in the condition as shown also in FIG. 28.

FIG. 38 illustrates a still further stage in the conveyor chain's travel at a point at the beginning of the wrapper edge fold down operation by the wrapping mechanism. In this view the trailing edge fold down finger 366 and the

trailing corner fold down shoe 367 is shown in full lines just prior to overtaking the upstanding edges and corners of the wrapper blank 55. The dotted line representation for the trailing edge fold down finger 366 indicates the initial action as it overtakes the related chain conveyor link 26 to effect a folding down of the trailing edge of the wrapper blank 55.

FIG. 39 illustrates a further stage slightly beyond that of FIG. 38 wherein the trailing corner fold down shoe 367 has overtaken the related chain link 26 to the extent of gathering in and folding down the trailing corners 65, 76, see FIG. 38, of the wrapper blank 55. It will of course be remembered that the chain 360 is driven at a velocity slightly greater than that of the conveyor chain links 26 so that as the chain 360 traverses its lower reach the finger 366 and shoe 367 gradually overtake the link to effect the trailing edge and trailing corner fold down function as was above described. At this stage the wrapper blank has been applied to the extent shown in FIG. 29.

FIG. 40 illustrates the same operation as shown in FIGS. 38, 39 but in plan view with reference to three separate locations of a chain conveyor link 26, indicating the progressive action of a fold down finger 366 and fold down shoe 367 with respect to a related one of the links 26. With respect to the most advanced link 26 shown in FIG. 40, the operation of the hold down blade 381 is shown. As will be seen, at that stage in the wrapping operation wherein the trailing edge and trailing corners are folded down, the blade 381 is projected outwardly in the articulated manner heretofore described into a hold down position between the bottom surface of shoe 367 and the folded trailing edge and trailing corners of the wrapper blank.

FIG. 41 shows a slightly later stage in the operation indicating the equal velocities of the hold down blade 381 and the chain conveyor links 26 as the links advance the formed product to the leading corner and leading edge fold down plow 385. As the formed product passes the plow, the folding edges 386, 387 thereof fold down the leading corners 63, 62 respectively of the wrapper blank while the trailing corners and edges are held folded by the hold down blade 381. At this point the retaining tip 402 is disposed just behind the leading edge 61 of the wrapper blank, traveling at the same velocity therewith so as to prevent the central portion of the leading edge 61 from accidentally folding down with the leading corners 62, 63. This is the stage of wrapping shown in FIG. 30. The retainer tip 402 rides through the elongated slot 388 in plow 385 until it approaches the end of the slot whereupon it rises out of the slot to a nonretaining position while the hold down blade 381 at the same time is withdrawn from a hold down position, whereupon the central area of the leading edge 61 is folded down as the wrapper blank rides past the end of the slot 388 to assume the condition shown in FIG. 31.

FIG. 42 also illustrates the retaining function of the tip 402, FIG. 42 showing in side elevation the retaining function of the tip 402 carried by chain 397 in holding upright the leading edge 71 of the wrapper blank while the leading corners thereof are being folded down.

From the foregoing description of the apparatus and the method by which it functions, it will be apparent that the invention as is embodied therein achieves novel packaging results having many advantageous aspects. Although the invention has been described herein with respect to utilization of a wrapper blank formed of two plies of sheet material coated with a thermoplastic substance, it should of course be understood that the same results could be achieved without utilization of coated sheet material if the sheet material itself were made of a thermoplastic substance. Furthermore, wrapper blanks formed of a single ply of sheet material can be utilized with advantageous results, in which case the separate means for supplying and feeding the sheet material 33 could be eliminated.

While there has been shown and described what is considered to be a preferred embodiment of the invention, it should of course be understood that obvious changes in form and details could be made without departing from the spirit of the invention. It is, therefore, intended that the invention be not limited to the specific form and function herein disclosed nor to anything less than the whole of the invention hereinabove set forth and as hereinafter claimed.

We claim:

1. Product packaging apparatus comprising, a continuously driven conveyor adapted to receive a wrapper blank, means for delivering the product to be formed and wrapped onto said wrapper blank, means continuously driven in synchronism and registration with said conveyor and actuatable while said conveyor carries said blank through one stage of its travel for compacting said product into a predetermined form while partially applying said blank around said form, means for folding the edges of said blank to completely enwrap the blank about said form, and means for sealing said edges to enseal the formed product within said wrapper blank.

2. The invention according to claim 1 wherein said conveyor is strung around an endless path and carries the product to be formed and wrapped into operative position relative to said compacting means, folding means, and sealing means in succession.

3. Product packaging apparatus comprising, a continuously driven conveyor adapted to receive a wrapper blank, means for delivering the product to be formed and wrapped onto said wrapper blank, means driven in synchronism with said conveyor for compacting said product into a predetermined form while partially applying said blank around said form, means for folding the edges of said blank to completely enwrap the blank about said form, and means for sealing said edges to enseal the formed product within said wrapper blank, said conveyor comprising a chain consisting of individually interconnected links, each link being adapted to receive a wrapper blank thereon and shaped to define a mold by which the shape of the product to be wrapped is formed.

4. Product packaging apparatus comprising, a continuously driven conveyor adapted to receive a wrapper blank, means for delivering the product to be formed and wrapped onto said wrapper blank, means driven in synchronism with said conveyor for compacting said product into a predetermined form while partially applying said blank around said form, means for folding the edges of said blank to completely enwrap the blank about said form, and means for sealing said edges to enseal the formed product within said wrapper blank, said product forming means being disposed on opposite sides of said conveyor and including members adapted to register with a wrapper blank and the product delivered thereto along one stage in the path of said conveyor, said forming means being coactuable along an axis perpendicular to the plane of said conveyor for compacting said product into said predetermined form.

5. The invention according to claim 4 wherein both of said members are driven towards each other into product forming position so that both sides of said form will be sharply defined.

6. Product packaging apparatus comprising, a continuously driven conveyor adapted to receive a wrapper blank, means for delivering the product to be formed and wrapped onto said wrapper blank, means driven in synchronism with said conveyor for compacting said product into a predetermined form while partially applying said blank around said form, means for folding the edges of said blank to completely enwrap the blank about said form, and means for sealing said edges to enseal the formed product within said wrapper blank, said folding means including devices driven at a greater velocity than that of said conveyor to cause said devices to overrun the partially wrapped product forms carried by said

conveyor to fold down the trailing edges of the wrapper blanks partially wrapped around said forms.

7. Product packaging apparatus comprising, a continuously driven conveyor chain consisting of individually interconnected links, each adapted to receive a wrapper blank and shaped to define a mold for forming said product, product compacting members driven in synchronism with said conveyor and disposed on opposite sides thereof, said members being actuatable along an axis transverse to the plane of said conveyor and registering with each link for mutually compacting said product into the shape defined by said mold while at the same time partially applying said wrapper blank around the formed product, means for folding the edges of said blank to completely enwrap said blank about said form, said folding means including devices driven at a greater velocity than that of said conveyor for causing said devices to overrun said partially wrapped forms to fold down the trailing edges of said blanks, and means for sealing the folded down edges of said blank to enseal the formed product within said wrapper blank.

8. Product packaging apparatus comprising, a continuously driven conveyor adapted to receive a wrapper blank, means for delivering the product to be formed and wrapped onto said wrapper blank, means for measuring the amount of product delivered to said wrapper blank, means driven in synchronism with said conveyor for compacting said measured amount of product into a predetermined form while partially applying said blank around said form, means for folding down the edges of said wrapper blank to completely enwrap the blank about said form, and means for sealing the edges of said blank to enseal the formed product within said wrapper blank.

9. The invention according to claim 8 wherein said conveyor is strung around an endless path and carries the product to be formed and wrapped into operative position relative to said compacting means, folding means and sealing means in succession.

10. The invention according to claim 8 wherein said conveyor comprises a chain consisting of individually interconnected links, each link being adapted to receive a wrapper blank thereon and shaped to define a mold by which the shape of the product to be wrapped is formed.

11. The invention according to claim 8 wherein said product forming means are disposed on opposite sides of said conveyor and are adapted to register with a wrapper blank and the product delivered thereto along one stage in the path of said conveyor, said members being coactuable along an axis perpendicular to the plane of said conveyor but compacting said product into said predetermined form.

12. The invention according to claim 8 wherein both of said members are driven towards each other into product forming position so that both sides of said form will be sharply defined.

13. The invention according to claim 8 wherein said folding means include devices driven at a greater velocity than that of said conveyor to cause said devices to overrun the partially wrapped product forms carried by said conveyor to fold down the trailing edges of the wrapper blank partially wrapped around said formed product.

14. The invention according to claim 8 wherein said measuring means includes an open cup-shaped member for containing the amount of said product to be formed and wrapped, said cup-shaped member being driven in unison with said conveyor, and means for limiting the amount of product contained by said cup-shaped member to a predetermined level.

15. Product packaging apparatus comprising, a continuously driven conveyor chain consisting of individually interconnected links, each adapted to receive a wrapper blank and shaped to define a mold for forming said product, means for forming a wrapper blank from continuous

sheet material and applying a blank to said conveyor, means for delivering the product to be formed and wrapped onto said wrapper blank, measuring means for determining the amount of product to be formed, said measuring means including a cup-shaped member for containing a charge of product to be formed and wrapped, means driven in synchronism with said conveyor for compacting said measured amount of product into a predetermined form while partially applying said blank around said form, means for folding down the edges of said wrapper blank to completely enwrap the blank about said form, and means for sealing the edges of said blank to enseal the formed product within said wrapper blank.

16. In a packaging apparatus having a continuously driven conveyor for transporting a formed product partially enclosed by a wrapper blank, the edges of which are upstanding in a direction perpendicular to the path of said conveyor, a wrapping mechanism for completing the enclosure of the product, said mechanism including a second conveyor disposed to run in parallel with said first mentioned conveyor and driven at a greater velocity than that of said first mentioned conveyor, and devices carried by said second conveyor for folding down the trailing edge of said wrapper blanks while overrunning the products being transported by said first mentioned conveyor.

17. The invention according to claim 16 wherein each said device includes a finger member for folding down the central area of said trailing edge and a yoke shaped shoe member for gathering in and folding down the corner areas of said trailing edge.

18. The invention according to claim 16 including hold down members driven from a third conveyor running parallel to said first mentioned conveyor and at the same velocity therewith, said hold down members being disposed to overlie and hold down the folded over trailing edge and corners of said wrapper blank after said fold down devices are rendered ineffective.

19. The invention according to claim 18 wherein said hold down members are articulated so as to move into hold down position in a direction perpendicular to the path of said first mentioned conveyor, the articulation being effected by the relative displacement of two pivotal axes about which said hold down member may rotate, one of said pivotal axes lying in the path of said third conveyor, the other of said pivotal axes lying in a cam track asymmetrical to said third conveyor.

20. In a packaging apparatus having a continuously driven conveyor for transporting a formed product partially enclosed by a wrapper blank, the edges of which are upstanding in a direction perpendicular to the path of said conveyor, a wrapping mechanism for completing the enclosure of said product, said mechanism including a second conveyor disposed to run in parallel with said first mentioned conveyor and driven at a greater velocity than that of said first mentioned conveyor, fold down fingers carried by said second conveyor for folding down the trailing edge of said wrapper blanks while overrunning said product being transported by said first mentioned conveyor, fold down shoes carried by said second conveyor for folding down the trailing corners of said wrapper blanks while overrunning said product being transported by said first mentioned conveyor, and a hold down member carried by a third conveyor running in a path parallel to that of said first mentioned conveyor and at the same velocity therewith, said hold down member being disposed to overlie said folded down trailing edge and corners of said wrapper blank after said fold down members are rendered ineffective, said hold down members being articulated so as to move into and out of fold down position along a direction perpendicular to the path of said first mentioned conveyor, said articulation being effected by the relative displacement of two pivotal axes about which said hold down member may rotate, one of said pivotal axes lying in the path of said third conveyor,

the other of said pivotal axes lying in the path of a cam track asymmetrical with said third mentioned conveyor.

21. In a packaging apparatus having a continuously driven conveyor for transporting a product partially enclosed by a wrapper blank, the edges of which are upstanding in a direction perpendicular to the path of said conveyor and carry a tab secured to the central portion of the leading edge, a wrapping mechanism for completing the enclosure of said product, said mechanism including a second conveyor disposed to run in parallel with said first mentioned conveyor and driven at a greater velocity than that of said first mentioned conveyor, devices carried by said second conveyor for folding down the trailing edge and trailing corners of said wrapper blanks while overrunning the product being transported by said first mentioned conveyor, and plow means for folding down the leading corners of said wrapper blank prior to folding the central portion of the leading edge of said wrapper blank.

20. 22. The invention according to claim 21 including means for positively preventing the folding down of the central portion of the leading edge of said wrapper blank prior to the folding down of the leading corners thereof.

23. The invention according to claim 22 including means for holding down the trailing edge and trailing corners of said wrapper blank after said fold down means become ineffective and until the leading corners of said wrapper blank are folded down by said plow means.

24. In a packaging apparatus having a continuously driven conveyor for transporting a product partially enclosed by a wrapper blank, the edges of which are upstanding in a direction perpendicular to the path of said conveyor, a wrapping mechanism for completing the enclosure of said product, said mechanism including a second conveyor disposed to run in parallel with said first mentioned conveyor and driven at a greater velocity than that of said first mentioned conveyor, devices carried by said second conveyor for folding down the trailing edge and corners of said wrapper blanks while overrunning the product being transported by said first mentioned conveyor, plow means for folding down the leading edge and corners of said blank, and means driven in unison with said first mentioned conveyor for applying heat and pressure to the folded over edges and corners to seal said wrapper blank around said product.

25. The invention according to claim 24 wherein the means for applying heat and pressure to the folded over edges of said wrapper blank include a plurality of heated platens mounted on a member rotatable with said conveyor, and including means for displacing said member to prevent application of heat and pressure to the folded over edges of said wrapper blank.

26. A product packaging process comprising, fabricating individual wrapper blanks from continuous sheet material, transporting each of said blanks continuously in a flat horizontally disposed state along a prescribed course, depositing the product to be formed onto a blank while it progresses through one stage of said course, compacting said product into a predetermined form while partially applying said blank around said form as it progresses through another stage of said course, folding the edges of said blank into overlapping folds to completely enwrap said form, and joining said overlapping folds together to enseal the product within said blank.

65. 27. The invention according to claim 26 wherein the compacting of said product is achieved by applying pressure to opposite sides of the product deposited on said blank and along an axis perpendicular to the plane in which said blank is disposed.

70. 28. The invention according to claim 26 wherein the compacting of the product deposited on said blank is achieved by applying force to opposite sides of said product in succession, said forces being applied along an axis perpendicular to the plane in which said wrapper blank lies.

29. A product packaging process comprising, fabricating individual wrapper blanks from continuous sheet material, transporting said blanks continuously in a flat horizontally disposed state along a prescribed course, depositing the product to be formed onto said blanks, measuring the volume of the deposited product and removing all product in excess of a predetermined volume, compacting said measured product into a predetermined form while partially applying said blank around said form, folding down the edges of said blank into overlapping folds to completely enwrap said form, and joining said overlapping folds together to enseal the product within said blanks.

30. The invention according to claim 29 wherein said compacting is achieved by applying pressure to opposite sides of the product deposited on said blank and along an axis perpendicular to the plane in which said blank is disposed.

31. The invention according to claim 29 wherein said compacting step is achieved by applying force to opposite sides of said product in succession, said forces being applied along an axis perpendicular to the plane in which said wrapper blank is disposed.

32. The process of wrapping a formed product partially enclosed by a wrapper blank having upstanding edges comprising, conveying said product and blank continuously over a prescribed course, continuously transporting a fold-down device at a velocity greater than the velocity at which said product is conveyed and along an endless course of which one section is parallel with said prescribed course, said device operating when traversing said section to overtake the conveyed product and fold down the trailing edge and corners of the upstanding wrapper blank partially enclosing the product.

33. The invention according to claim 32 including the step of folding down the leading edge and corners of said wrapper blank subsequent to the folding down of the trailing edge and corners.

34. The invention according to claim 33 including the

step of holding down the folded trailing edge and corners of said wrapper blank after said devices have become ineffective and until the leading edge and corners have been folded down.

35. The process of wrapping a formed product partially enclosed by a wrapper blank having upstanding edges of which the leading edge carries a tab comprising, conveying said product and blank continuously over a prescribed course, continuously transporting a fold down device at a velocity greater than the velocity at which said product is conveyed and along an endless course of which one section is parallel with said prescribed course, said device operating to overtake the conveyed product and fold down the trailing edge and corners of the upstanding wrapper blank partially enclosing the product, folding down the leading edge and corners of said wrapper blank subsequent to the folding down of the trailing edge and corners, and sealing together the folded down edges and corners to completely enseal said product with in said wrapper blank.

36. The invention according to claim 35 including the step of positively restraining the folding down of the leading edge of said wrapper blank until after the leading corners have been folded down.
